MUFFLER

Harry A. R. Klemm, Rutherford, N. J.

Application October 16, 1942, Serial No. 462,218

5 Claims. (Cl. 181—48)

The invention relates to mufflers and more particularly to mufflers of the type incorporated in automotive vehicles for silencing the exhaust gases of the internal combustion engines of such vehicles.

The invention has for its object to provide a muffler constructed in a novel manner adapting it for efficient association with a variety of different types of engines and vehicles in which the latter are embodied.

The invention contemplates further the provision of a muffler capable of being adjusted lengthwise and rotatably to fit different engines and vehicles, without in any way affecting its efficiency and without requiring any particular skill on the part of the mechanic.

Other objects will appear from the description hereinafter and the features of novelty will be pointed out in the claims.

In the accompanying drawing which illustrates an example of the invention without defining its limits,

Fig. 1 is a longitudinal section of the novel muffler;

Fig. 2 is a cross-section on the line 2—2 of Fig. 1;

Fig. 3 is a similar view on the line 3—3 of Fig. 1;

Fig. 4 is an end view of the muffler, and

Fig. 5 is a fragmentary enlarged section of clamping means included in the muffler.

The novel muffler comprises a plurality of hollow sections adjustably associated with each other and provided interiorly with muffling means, said muffle further including a secondary inlet and secondary outlet capable of being adjusted to a plurality of operative positions.

In its illustrated form the novel muffler comprises a hollow main section 10 and opposite hollow end sections 11 and 12 telescopically fitted into said main section 10 and adjustable in axial directions relatively thereto. In the preferred form the sections 10, 11 and 12 are cylindrical in form so as to be capable of rotation relatively to each other about the longitudinal axis of the muffler. For convenience the end section 11 may be termed the inlet end section, in which case the other end section may be referred to as the outlet end section. It will be understood however that, in practice, the muffler is reversible and that either end section 11 or 12 may serve as an inlet or outlet section and may be selectively utilized as such.

The outer ends of the sections 11 and 12 are provided with end plates 13 and 14 respectively,

and secured in place in any convenient manner as by welding or the like. In the illustrated example the end plates 13 and 14 are fitted into the ends of the sections 11 and 12 and are provided with annular flanges 15 lying in surface engagement with the inner surfaces of said end sections 11 and 12 and secured thereto in any well-known manner, as by welding. The end plates 13 and 14 are provided with inwardly directed annular bosses 16 and 17 respectively, for the purpose to be fully set forth hereinafter.

The muffling means within the sections of the muffler may be of any suitable construction, and as shown, comprises baffles 18 having perforations 19 and suitably secured in place as by welding or the like, preferably in the end sections 11 and 12 at the respective inner ends thereof. In addition the illustrated muffling means comprises tubes 20 and 21 having one end mounted on the respective bosses 16 and 17 and extending through the baffles 18 into telescopic slidably engagement with each other as shown in Fig. 1. The tubes 20 and 21 are provided with perforations 22 which establish communication between the interiors of said tubes 20 and 21 and the interiors of the sections 10, 11 and 12 which surround said tubes 20 and 21.

The bosses 16 and 17 are internally screw-threaded for the accommodation selectively of a suitable outlet adapter 23 or closing plug 24, and are located at the centers of the respective end plates 13 and 14. Similarly the tubes 20 and 21 register with the major longitudinal axis of the muffler and with the bosses 16 and 17 constitute what is commonly known as the through-pass of said muffler.

In addition to the parts so far described, the end plates 13 and 14 are provided with secondary annular bosses 25 and 26 respectively, located 40 radially outward relatively to the bosses 16 and 17. The secondary annular bosses 25 and 26 are internally screw-threaded for the accommodation selectively of a suitable inlet adapter 27 or closing plug 28 which may be a duplicate of the previously mentioned plug 24. The secondary annular bosses 25 and 26 constitute secondary inlets and outlets which are adjustable to a plurality of operative positions by rotating the sections 11 and 12 relatively to the section 10.

The muffler further includes novel clamping means whereby the sections 10, 11 and 12 are releasably fixed against relative movement, and specifically in practice, whereby the end sections 55 11 and 12 are releasably secured against axial and

rotative movements relatively to the main section 10.

In its illustrated form the clamping means comprises flexible clamping bands 29 of metal or other suitable material having their opposite free end coiled upon themselves to form bearings 30 and 31 respectively, for preferably cylindrical members 32 and 33, respectively. Each member 33 is provided with a transverse opening 34 adapted to register with openings 35 formed at opposite points in the bearing 30, and each member 33 is provided with an internally screwthreaded opening 36 arranged to register with openings 37 of the bearing 31.

The clamping means further includes bolts 38 which pass loosely through the openings 35 and transverse opening 34, and at least one opening 37 into screwthreaded engagement with the opening 36 of each clamping band 29.

With this arrangement the clamping bands 29 will be contracted and expanded as the bolts 38 are screwed into or out of the openings 36 of the members 33. At the same time the members 32 and 33 will automatically adjust themselves for proper co-operation with the bolts 38 as contraction and expansion of the bands 29 takes place.

In practice, the novel muffler is installed in the automotive vehicle in the customary manner. If the installation is such as to permit this to be done, the adapter 27 is threaded into the boss 16 and connected thereby with the exhaust of the engine through the medium of the conventional exhaust outlet 39. In such case the plug 28 is threaded into the secondary boss 25 to close the secondary inlet thereof. If this arrangement is not possible because of specific construction and location of the engine exhaust 39, the closing plug 28 may be screwed into the boss 16 and the adapter 27 threaded into the secondary boss 25. The end section 11 may then be rotated relatively to the main section 10 to bring the adapter 27 into the proper operative position for efficient connection with the exhaust pipe 39.

Similarly the adapter 23 may be threaded into the boss 17 at the outlet end of the muffler for connection with the tail pipe 40 through which the exhaust gases escape to the atmosphere. In such case the plug 24 will be threaded into the secondary boss 26. On the other hand, if this is not feasible because of special and specific associate construction, the adapter 23 may be threaded into the secondary boss 26 and the plug 24 in such case threaded into the boss 17. The outlet section 12 may then be rotated relatively to the main section 10 to bring the adapter 23 into proper operative position for connection with the tail pipe 40.

It will be understood that prior to the rotative adjustments of the end sections 11 and 12 relatively to the main section 10, the bolts 38 are unscrewed or loosened to relieve the clamping action of the clamping bands 29 to thereby facilitate the aforesaid rotative adjustment of the end sections 11 and 12. Subsequent to this latter adjustment and after the adapters 23 and 27 or either of them have been set in the most efficient operative positions, the bolts 38 are screwed into the members 33 to thereby contract the clamping bands 29 into clamping engagement with the section 10 which is thereby caused to clamp the end sections 11 and 12 against rotative movement relatively to the main section 10.

Likewise the axial length of the muffler may be adjusted to properly meet the conditions of any

installation by simply relieving the clamping pressure of the clamping bands 29 as previously described herein, whereupon one or both of the end sections 11 and 12 may be telescopically adjusted into or out of the main section 10 until the desired and proper length of muffler has been attained. The clamping bands 29 are thereupon contracted by manipulation of the bolts 38 to fix the end sections 11 and 12 or either of them in the adjusted position.

In some cases the muffler may include only one end section telescopically and rotatably combined with the main section 10 to provide for the aforesaid adjustments.

The universal adjustability of the novel muffler enables it to be used efficiently in any installation and to be operatively installed in a simple manner and without requiring any particular skill on the part of the mechanic.

Because of this universal adjustability, it is unnecessary for instance for a garage or repair shop to maintain on hand a large stock of different types of specially constructed mufflers to meet the requirements of different types of automotive vehicles and different types of power plants therein. With the instant novel universal adjustable muffler only a relatively small supply thereof need be maintained to enable the garage or repair shop to meet any installation requirements which may arise.

Various changes in the specific form shown and described may be made within the scope of the claims without departing from the spirit of the invention.

I claim:

1. A muffler of the kind described comprising a plurality of hollow sections rotatably associated with each other, an end plate provided in the outer end of one of said sections, muffling means within said sections, and an inlet connection on said end plate rotatably adjustable thereby about the axis of the muffler to a plurality of operative positions.

2. A muffler of the kind described comprising a plurality of hollow sections rotatably associated with each other, an end plate provided in the outer end of one of said sections, muffling means within said sections, and a tail pipe connection on said end plate rotatably adjustable thereby about the axis of the muffler to a plurality of operative positions.

3. A muffler of the kind described comprising a plurality of hollow sections rotatably associated with each other, end plates provided in the outer ends of said sections, muffling means within said sections, an inlet connection on the end plate of one of said sections rotatably adjustable thereby about the axis of the muffler to a plurality of operative positions, and a tail pipe connection on the end plate of another of said sections rotatably adjustable thereby about the axis of the muffler to different operative positions relatively to said inlet connection.

4. A muffler of the kind described comprising a cylindrical tubular main section, a cylindrical tubular end section telescopically and rotatably associated with said main section for axial and rotative adjustment relatively thereto, telescopically and rotatively combined muffling means within said sections axially and rotatively adjustable therewith, a plurality of connections located on said end sections in registry with the axis thereof and in radially outward spaced relation to said axis respectively, the radially outward spaced connections being adjustable by the

relative rotation of said end sections to selected operative positions, and means for fixing said sections and muffling means in adjusted positions.

5. A muffler of the kind described comprising a cylindrical tubular main section, inlet and outlet end sections telescopically associated with said main section for axial and rotative adjustment relatively thereto, end plates carried by said end sections at the respective outer ends thereof, annular bosses projecting inwardly from the respective end plates at the centers thereof to provide central inlet and outlet connections, perforated baffles carried by said end sections at the respective inner ends thereof, perforated tubes connected with said bosses and extending through 10 15 said baffles into telescopic association with each other and partaking of the axial and rotative

adjustments of said end sections to provide an adjustable through passage in said muffler, secondary annular bosses projecting inwardly from said end plates in spaced radial outward relation to the first named bosses and providing secondary inlet and outlet connections adapted to be rotatably adjusted about the axis of the muffler to a plurality of operative positions by the rotation of said end sections relatively to said main section, clamping means for clamping said end sections in adjusted positions, and plugs for connection with selected bosses to close the inlet and outlet connections which are not in use at a given time and with a given adjustment of said sections.

HARRY A. R. KLEMM.
